[57] CLAIM

The ornamental design for a toy balancing beam, as shown and described.

DESCRIPTION

FIG. 1 is a front elevational view of a toy balancing beam showing my new design;
FIG. 2 is a top plan view thereof; and
FIG. 3 is a right side elevational view thereof, the side opposite being substantially a mirror image;
FIG. 4 is a rear elevational view thereof; and
FIG. 5 is a bottom plan view thereof.

FIG.1

FIG.2

FIG.3

FIG. 4
